UNITED STATES PATENT OFFICE.

CLARENCE BESAW, OF HAMMOND, NEW YORK.

CURTAIN-HANGER.

1,229,018.

Specification of Letters Patent.

Patented June 5, 1917.

Application filed August 30, 1916. Serial No. 117,760.

To all whom it may concern:

Be it known that I, CLARENCE BESAW, a citizen of the United States, residing at Hammond, in the county of St. Lawrence, 5 State of New York, have invented a new and useful Curtain-Hanger; and I do hereby declare the following to be a full, clear, and exact description of the invention, such as will enable others skilled in the art to 10 which it appertains to make and use the same.

The present invention relates to a curtain pole and supporting means therefor, and has for its object to provide a device 15 of this character which embodies novel features of construction whereby it can be readily applied to a window casing without marring or injuring the same.

Further objects of the invention are to 20 provide a curtain hanger which is comparatively simple and inexpensive in its construction, which can be adjusted to fit different sizes of window casings, which can be easily placed in position or removed 25 therefrom, without injuring the window casing, and which will support the curtain in proper position.

With these and other objects in view, the 30 invention consists in certain novel combinations and arrangements of the parts as will more fully appear as the description proceeds, the novel features thereof being pointed out in the appended claims.

For a full understanding of the invention, reference is to be had to the following 35 description and accompanying drawing, in which:—

Figure 1 is a front elevation of a curtain pole constructed in accordance with the invention, showing the same as applied to a 40 window casing.

Fig. 2 is a top plan view of the same.

Fig. 3 is an enlarged detail view of one 45 end of the curtain pole, portions being broken away and shown in section.

Fig. 4 is a view similar to Fig. 3, showing a slight modification.

Corresponding and like parts are referred to in the following description and 50 indicated in all the views of the drawings by the same reference characters.

Referring to the drawings, which illustrate one embodiment of the invention, the 55 numeral 1 designates a curtain pole which is of a proper length to extend across the

front of a window casing A, and of a suitable size to receive the usual rings of a curtain. The ends of the pole 1 are threaded to receive the knobs 3 which are adjustable thereon, the inner ends of the knobs bearing against square outer faces 4^a of blocks 4 which are slidable upon the curtain pole. These blocks 4 are formed with openings which loosely receive the curtain pole, and are enlarged at their inner ends where they 60 terminate in the square faces 4^b, said faces being of a sufficiently extended area to engage the edges of the curtains and hold them in proper position.

Projecting rearwardly from each of the 70 blocks 4 is an outwardly and inwardly curved arm 5, said arms terminating in elongated vertical jaws 6 which are adapted to engage the sides of the window casing A. The gripping faces of the jaws 6 are elongated so as to extend over a comparatively large area, and are preferably rounded so that there will be no sharp corners to bite into the window casing and permanently 75 deface the same. The curved arms 5 may 80 either be integral with the blocks 4, as shown by Fig. 1, or pivotally connected to the blocks and engaged by strong springs 7, as indicated by Fig. 4, said springs serving to hold the jaws in position, and being 85 of assistance when mounting the device upon the window casing.

In order to apply the curtain hanger to the window casing, the blocks 4 are assembled upon the pole 1 and the jaws 6 placed 90 in engagement with the sides of the window casing. The knobs 3 are then screwed tightly against the blocks 4, thereby sliding the same inwardly upon the curtain pole and causing the jaws 6 to forcibly grip the 95 window casing. Owing to the fact that the jaws are elongated vertically and cover an extended area they may be caused to grip the window casing with sufficient force to hold the device in position and support 100 the curtain, without danger of permanently marring or injuring the window casing. Where the arms 5 are pivoted to the blocks, the springs 7 will assist in holding the device in position while tightening the knobs 105 3, although before the knobs are finally screwed home, the arms 5 preferably engage shoulders 8, thereby obtaining a rigid clamping action when the device is finally mounted in position.

Having thus described the invention, what I claim as new and desire to secure by Letters Patent, is:—

1. A curtain hanger including a pole having threaded ends, blocks slidably mounted upon the end portions of the pole and terminating at their inner ends in enlarged and vertically disposed square faces adapted to engage and confine the curtain, the outer ends of the blocks being rounded, knobs threaded upon the ends of the curtain pole and engaging the rounded outer ends of the blocks, horizontally disposed inwardly curved arms projecting rearwardly from the blocks, and vertically elongated jaws carried by the ends of the curved arms for engagement with the sides of a window casing to support the pole in operative position.

2. A curtain hanger including a pole, 20 blocks applied to the ends of the pole, one of the blocks being slideable thereon, means for forcibly moving the said slideable block toward the opposite block, rearwardly projecting arms pivotally connected to the blocks, vertically elongated jaws carried by the arms and adapted to engage opposite sides of a window casing, and springs acting upon the jaws to hold them in operative position. 25

30 In testimony whereof I have signed my name to this specification in the presence of two subscribing witnesses.

CLARENCE BESAW.
